(57) **CLAIM**

The ornamental design for a charging dock, as shown and described.

DESCRIPTION

FIG. 1 is a front perspective view of a charging dock showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is another front perspective view thereof.

The broken lines depicting the remainder of the charging dock in FIGS. 1-8 show features that form no part of the claimed design.

1 Claim, 6 Drawing Sheets
